MATERIAL TRAP**Joseph H. Morrow, Hokendauqua, Pa., assignor to
Fuller Company****Application December 15, 1951, Serial No. 261,874****1 Claim. (Cl. 209—474)**

This invention relates to apparatus for removing undesired substances from fine dry materials, and more particularly, the invention has to do with the separation by gravity of foreign objects from a moving stream of pulverulent material, and their collection in a fixed bed of fluidized material.

In the processing and handling of many pulverulent materials, undesired objects and particles of greater density than the pulverulent material are frequently introduced and must be removed before a subsequent processing or handling operation can be carried out. For example, in grinding a chemical, rock, or mineral, there is usually introduced into the mill stream a variety of metal objects, such as broken pieces of grinding media, mill liners, screen wire, and other metallic items resulting from wear and breakage, all of which are commonly referred to as "tramp iron." Undesired oversize particles are also frequently present in the pulverulent material being discharged from a mill and must be separated. In other manufacturing operations, such as conveying and elevating dry materials, tramp iron also enters the material stream due to wear and breakage of equipment.

Magnetic separators associated with a moving stream of material in a spout, or in a conveyor, have long been used successfully to remove tramp iron, but such devices are restricted to the separation of magnetically susceptible materials. Tramp iron and also oversize particles are commonly removed from dry materials by vibrating screens. In the screening of large tonnages of fine dry materials, and particularly abrasive substances, however, operating and maintenance costs are high, and there is always present the chance that a broken or worn screen will pass a substantial quantity of foreign material before the defect is discovered and repaired, the repair in many instances involving costly shutdowns of major plant operations.

The passage of air through a distribution means into a body of dry material, either with or without mechanical vibration, has previously been employed to cause a classification into components according to particle size or specific gravity. Such air classification methods have been successful in certain industries with a limited number of materials which are in general coarser in size than those to which my invention is applicable. The efficiency of classification decreases rapidly as the average particle size decreases from a "crusher product size" through the "granular" or "sand size" down to pulverulent materials. In the case of pulverulent materials, the amount of classification obtained is negligible, the result of diffusing relatively small volumes of air therethrough being largely the production of a fluidized bed, more fully described below.

The present invention is accordingly directed to a novel and simple apparatus for removing, from a moving stream of pulverulent material, foreign or undesired substances of greater density than the material, by the use of a fluidized bed through which the substantially greater density mate-

2

rial settles. The apparatus of my invention has the further advantage of not in itself being able to introduce contamination due to wear or breakage and of not permitting foreign materials already in the stream to pass because of defects due to wear.

The separation of foreign substances of greater density from a stream of moving material is accomplished in accordance with my invention by maintaining a fixed bed of the material, diffusing air through the bed to fluidize the material therein, and causing the moving stream to travel over the top of and in contact with the top of the fluidized bed. The undesired foreign material having a density higher than the particles in the moving stream, either due to a higher specific gravity, or to a substantially larger particle size, settles from the moving stream under the influence of gravity through the fixed bed of material of reduced bulk density, so that it can be removed at the bottom of the bed.

The apparatus of my invention, referred to as a material trap, includes a chamber for containing a column of fluidized pulverulent material and adapted to be placed below an opening through the bottom of a trough or like structure, along which the pulverulent material is being advanced. A gas permeable medium forms the bottom of the chamber and serves as a means for diffusing air or other suitable gas into the pulverulent material to maintain it in a fluidized condition, and a plenum chamber is disposed below the porous medium.

It is well known that the introduction of a gas, in appropriate quantities, into a pulverulent material by diffusion will result in fluidization of the mass, and the gas-solids mixture will acquire many of the properties of a liquid. Individual particles will be separated from each other, the bulk volume considerably expanded and thus the bulk density reduced, and the internal particle to particle friction reduced. To maintain the fluidized condition in a column the gas must have sufficient velocity to support the particles, but not sufficient to entrain any substantial amount of solid as the gas emerges from the upper surface of the bed.

My material trap includes the use of such a fluidized bed of reduced bulk density, and the heavier tramp iron or oversize particles sink readily through the bed, a movement which would not be possible in an un aerated bed due to the internal friction and close packing of the fine particles.

As previously stated, the gas emerging from the upper surface of the fixed bed is directed through the moving stream of material producing a fluent effect similar to that in the fixed bed. As a result, the tramp iron and oversize particles settle out of the stream and into the fluidized bed.

The apparatus of my invention may be applied to the separation of foreign material from a variety of pulverulent substances among which may be mentioned for purposes of illustration: cement and cement raw materials, gypsum, soda ash, fly ash, barytes, bentonite, flour, hydrated lime, ground ores, alumina, catalysts, silica, phosphates, talc, resins, and detergents. Generally speaking, any of the above materials, to be effectively fluidized in my trap, should be finer than 20 mesh and preferably finer than 65 mesh, while at the same time containing a substantial proportion of minus 100 mesh, and with some materials a substantial amount of minus 200 mesh.

The moving stream of pulverulent material from which foreign material is separated, in accordance with my invention, may be present in a variety of conveyors. Typical examples are: the air activated gravity conveyor referred to below, screw conveyors, flight conveyors, drag chains and Redlers, and vibrating conveyors.

A clearer understanding of my invention may be had by reference to the drawings in which:

Fig. 1 is a schematic elevation of an air activated gravity conveyor utilizing my material trap;

Fig. 2 is a sectional view of the material trap disclosing a portion of the air activated gravity conveyor;

Fig. 3 is a transverse section along line 3—3 of Fig. 2;

Fig. 4 is a sectional view of the material trap disclosing a portion of a screw conveyor;

Fig. 5 is a transverse section along line 5—5 of Fig. 4;

Fig. 6 is a side elevation, partially in section, of a modified form of the material trap disclosing a portion 10 of a screw conveyor;

Fig. 7 is a transverse section along line 7—7 of Fig. 6;

Fig. 8 is an enlarged vertical section of the material trap disclosed in Fig. 6;

Fig. 9 is a side elevation, partially in section, disclosing an air activated gravity conveyor;

Fig. 10 is a vertical section of a second modified form of my material trap;

Fig. 11 is a transverse section along line 11—11 of Fig. 10.

Referring to the drawings, it will be seen that my material trap in its simplest form comprises a housing, or container, 1 in the form of a rectangular box-like structure. A gas permeable medium, or wall, 2 extends across the lower portion of the housing 1 and provides a material supporting surface which at the same time divides the housing into two portions, a plenum chamber 3 and a material confining chamber 4. The plenum chamber 3 is formed by a rectangular section 5, attached to the housing 1 by means of flanges and bolts 6, the gas permeable medium being held between the respective flanges of the housing and plenum chamber in a secure manner. Air, or other desired operating gas, enters the plenum chamber 3 through conduit 7 and is furnished from any convenient source, not disclosed. A clean-out port 8 is covered by a hinged closure 9 secured in a closed position by wing nuts 10.

Fig. 1 discloses a typical schematic arrangement of an air activated gravity material conveyor, a detailed description of which is found in U. S. Patent Nos. 2,527,455 and 2,527,488, utilizing my material trap in any of the specific forms. I have shown a conveying duct 11 delivering material from a hopper 12 to a receiver 13. A gas permeable medium 14 provides a material conveying surface which at the same time divides the conveyor into two portions, a conveying air plenum chamber 15 and a material conveying duct 16. The air is supplied by a fan 17 driven by a motor 18 through an appropriate connection 19 to the plenum chamber 15.

In the normal operation of the conveying duct 11, material capable of being fluidized is discharged from the hopper 12 onto the gas permeable medium 14, wherein it is fluidized by air passing through the gas permeable medium from the plenum chamber 15 and flows by gravity to the receiver 13 through the material conveying duct 16.

The material trap is incorporated into the conveying system, as generally disclosed in Fig. 1, by inserting an expansion joint 20 into the conveying duct 11 at the desired location of the trap. The expansion joint 20 provides an unobstructed opening for the material conveying duct 16, but forms closures 21 for the conveying air plenum chamber 15. The housing 1 of the material trap is connected to the expansion joint 20 by means of flanges and bolts 22 thereby forming a material tight structure integral with the conveying system wherein the material confining chamber 4 of the material trap is in direct communication with the material conveying duct 16.

In the operation of the material trap disclosed in Figs. 1, 2 and 3 the chamber 4 is filled with the material to be conveyed in a preliminary operation or, during the initial part of the conveying operation, the material being conveyed enters and fills the chamber. The material within chamber 4, referred to as the fixed bed of mate-

rial, rests upon the gas permeable element 2 and air from the plenum chamber 3 is diffused through the element 2 into the fixed bed in sufficient quantity and at the proper pressure to fluidize the bed. The bed fills the chamber 4 and the top of the bed forms the support over which the material being conveyed travels across the trap.

The material being conveyed, containing foreign material, moves down the conveyor through the material conveying duct 16. The foreign material being carried in the moving stream is usually moving along the surface of the conveyor gas permeable medium 14 due to its density being greater than that of the particles of material being conveyed. When the foreign material moving along the conveyor 11 reaches the fluidized fixed bed of material in the trap, the foreign material, being heavier, will fall by gravity through the fluidized column to the surface of the gas permeable medium 2, while the moving bed of material being conveyed will continue through the material conveying duct 16 toward the receiver 13. The foreign material collected in the trap is later removed through the clean-out port 8 at any convenient time when the conveyor is not in operation. The frequency of clean-out is dictated by the proportion of foreign material in the material stream. A bed of several inches of foreign material is not detrimental to maintenance of a fluidized bed above it.

Fig. 4 discloses my material trap incorporated into a conveying system utilizing a conventional screw conveyor. The structure of the material trap is the same as that shown in Figs. 2 and 3. A transition section 23 is welded, or connected in any conventional manner, to the trough 24 of the screw conveyor 25, surrounding an opening 26 in the trough 24. The material trap is attached to the transition section 23 by means of flanges and bolts 27 thereby forming a material tight structure integral with the conveying system wherein the material confining chamber 4 of the material trap is in direct communication with the interior of the conveying trough 24.

In the operation of the material trap disclosed in Figs. 4 and 5, air is supplied to the plenum chamber 3 in sufficient quantity and at sufficient pressure to fluidize the material supported by the gas permeable medium 2 in the material confining chamber 4. This material contained in the trap is either placed therein prior to the operation of the conveyor, or is collected from the material being conveyed after the start of operation of the conveyor. The air diffused through the gas permeable medium 2 creates a fluidized column of material in the material confining chamber 4 that extends upwardly into the stream of material in the screw conveyor 25.

The material being conveyed, containing foreign material, moves through the conveyor trough 24 by means of the rotation of the screw flight 28. The foreign material contained in this moving stream of material is distributed throughout the moving stream of material. As the material is pushed through the conveyor trough 24 by the screw flight 28, it is at least partially fluidized as it passes over the opening 26 in the conveyor trough above the material trap. As previously described, the foreign material sinks into the fluidized column of material in the material confining chamber of the trap and is deposited on the surface of the gas permeable medium 2, while the moving bed of proper material size will continue through the screw conveyor 25 towards the discharge end.

In Figs. 6, 7, 8 and 9, I show a modification of my invention. Referring to Fig. 8, it will be seen that the modified form of my material trap comprises a housing 40 provided with two aeration units 41 and 42 positioned to form generally a V-like, or wedge shaped, supporting structure within the housing 40. The aeration units 41 and 42, are similar in structure, each being

provided with a plenum chamber 43 formed by a rectangular section 44 having one side closed with a gas permeable medium 45. The plenum chambers 43 are supplied with air from any convenient source through connections 46.

The aeration unit 42 is longer than unit 41 and extends below the end of unit 41, so that aeration is provided throughout substantially the entire cross-sectional area of housing 40. The lower end of aeration unit 41 lies above and spaced from the lower end of unit 42, and a discharge opening 47 is formed between the adjacent ends of the units. The opening is surrounded by a valve seat 48 and a gate 49 attached to a valve shaft 50 operates with the seat to control flow through opening 47. A valve handle 51 is attached to the valve shaft 50 is used as a means for opening and closing the valve gate 49. A butterfly valve 52 is positioned beneath an opening 53 in the lower portion of the material trap and is fastened to the housing 40 in any conventional manner. The butterfly valve 52 is provided with a valve gate 54 operated by a valve handle 55.

An expansion joint 56 is positioned in the air activated gravity conveyor 11 at the desired location of the trap and provides an unobstructed opening for the material conveying duct 16, but forms a closure 57 for the conveying air plenum chamber 15. The housing 40 of the material trap is connected to the expansion joint 56 by means of flanges and bolts 58 thereby forming a material tight structure integral with the conveying system wherein the material confining chamber 59 of the material trap is in direct communication with the conveying duct 16.

In the operation of the modified form of the material trap disclosed in Figs. 8 and 9, air is supplied to the plenum chamber 43 through the connections 46 in sufficient quantity and at sufficient pressure to fluidize the material supported by the gas permeable medium 45 in the material confining chamber 59. The material contained in the trap is either placed therein prior to the operation of the conveyor, or is collected from the material being conveyed after the start of operation of the conveyor. The air diffused through the gas permeable medium 45 creates a substantially vertical fluidized column in the material confining chamber 59 that extends upwardly into the stream of material in the air activated gravity conveyor.

The material being conveyed, containing foreign material, moves down the conveyor through the material conveying duct 16. The foreign material being carried in the moving stream is usually moving along the surface of the conveyor gas permeable medium 14 due to its density being greater than the particles of material being conveyed. When the foreign material moving along the conveyor 11 reaches the fluidized fixed bed of material in the trap the foreign material, being heavier, will fall by gravity through the fluidized column to the opening 47 at the bottom of the V-like supporting structure formed by the two aeration units 44, while the moving bed of proper material size will continue through the material conveying duct to the discharge end. The foreign material will accumulate at the bottom of the V-like supporting structure until a sufficient amount is collected for discharge of the material trap.

This modified form of my invention permits the discharging of foreign materials from the trap without interrupting the flow of material through the conveyor 11. The foreign material is discharged from the trap by opening the gate 49 by the rotation of valve handle 51 thereby permitting the foreign material to discharge from the V-like supporting structure on to the top of valve gate 54 of the butterfly valve 52. After the material has been discharged from the supporting structure, the valve gate 49 is closed by rotating the valve handle 51 in the opposite direction thereby closing the discharge opening 47 and

permitting the further accumulation of foreign materials from the conveyor 11. The foreign material is finally discharged from the trap structure by opening valve 54 by rotating valve handle 55 to position the valve 54 in a vertical position. The foreign material will then fall by gravity from the material trap structure whereupon the valve 54 is returned to its horizontal position for the next cycle of foreign material discharge.

If desired, the expansion joint 56 may be provided with a material inlet duct 60 to permit the location of the material trap to be directly beneath a substantially vertical supply of material. In this event the material trap will serve not only as a means for removing foreign material from the moving stream, but will also serve as a means for cushioning the fall of the vertical body of material which becomes particularly important in an embodiment incorporating an air activated gravity conveyor wherein the impingement of material on the woven fabric may produce excessive wear.

Figs. 6 and 7 disclose a modified form of my material trap incorporated into a conveying system utilizing a conventional screw conveyor. The structure of the material trap is the same as that described for Figs. 8 and 9. A transition section 70 is welded, or connected in any conventional manner, to the trough 24 of the screw conveyor 25, surrounding an opening 26 in the trough 24. The material trap is attached to the transition section 70 by means of flanges and bolts 71 thereby forming a material tight structure integral with the conveying system wherein the material confining chamber 59 of the material trap is in direct communication with the interior of the conveying trough 24.

The operation of this modified form of my material trap is the same as that described for the operation of the material trap disclosed in Figs. 8 and 9, and the characteristics of the screw conveyor 25 are the same as those described for Figs. 4 and 5.

A second modified form of my material trap is shown in Figs. 10 and 11 wherein the material trap housing is in the form of a valve body 80 and the material confining chamber 81 is in the form of a corresponding rotating valve plug 82. The plug 82 is provided at each end with shafts 83 and 84 positioned in bearing housings 85 and 86 of the valve body 80. The shaft 83 is provided with an externally operated handle, not disclosed, for rotating the valve plug 82. An aeration unit 87, comprising a gas permeable medium 88 and a plenum chamber 89 is positioned in the lower portion of the valve plug 82 and serves as a material supporting surface for the material confining chamber 81. Air is supplied to the plenum chamber 89 to a conduit 90 passing into the valve body 80 through a hollow section of the valve plug shaft 84 in an airtight arrangement. The valve plug structure 82 forms an opening 91 in the upper portion of the plug opposite the aeration unit 88 for the admission of material into the material confining chamber 81. An opening 93 is provided in the lower portion of the valve body 80 to permit removal of the foreign material from the trap.

The second modified form of my invention is incorporated into the previous mentioned types of conveying systems by attaching the material trap to the expansion joint of the air activated gravity conveyor, or to the transition piece of the screw conveyor, by means of flanges 92. This arrangement will, as described before for the other conveyors, provide a material tight structure that permits a direct communication between the material being conveyed and the material confining chamber 81.

In the operation of this second modified form of my material trap, a fluidized column of material is maintained in the material confining chamber 81 and extends upwardly into the moving stream of material being conveyed, such a column being produced by the fluidizing effect created by the diffusion of air from the plenum chamber 89 through the gas permeable medium 88 into the material contained in the chamber 81. The material being con-

veyed will deposit the foreign material on the supporting surface of the aeration unit, as previously described.

The foreign material accumulated may be removed from the material trap, without interruption in the flow of the material being conveyed, by the rotation of the valve plug 82 one-half turn by means of the shaft 83 and the turning handle. This one-half turn will position the opening 91 of the valve plug in communication with the valve body opening 93, and permit the foreign material accumulated in the trap to be discharged therefrom by gravity. This rotation of the valve plug is only a momentary movement and the valve plug is immediately returned to its normal operating position for further accumulation of the foreign material being separated from the material being conveyed.

The efficiency of collection of my trap depends principally on first, the density of the foreign material; second, the degree of fluidization maintained in the fixed bed, which is measured by the bulk density of the fluidized material compared to its unaerated bulk density; third, the degree to which the material in the moving stream is aerated as it passes over the fluidized bed; and fourth, the length of the fluidized bed over which the moving stream passes. The properties of each material handled and particularly the particle size range will, as explained above, determine in each case the most desirable vertical gas velocity to maintain the fixed bed at a minimum bulk density. The moving stream as it passes over the fluidized bed should be aerated to the maximum possible extent without causing entrainment of the fines in the gas emerging from the top of the stream. The most desirable length for the trap is dependent on the first three items listed above, and on the efficiency of separation desired. I have found that in general, satisfactory separation is achieved by using a width approximately the width of the conveyor trough, and a length of approximately two feet. For example, traps varying in width from 6 to 16 inches and two feet in length have been effective when used with air gravity conveyors. In the case of screw conveyors, the length of the trap is with advantage made equal to about one to two screw flights. This length normally gives the gas sufficient time to penetrate the moving stream, and the foreign material sufficient time to drop into the trap.

The depth of the fluidized bed employed will be determined by the properties of the pulverulent material, the amount of foreign material to be collected, and the preferred frequency of removing the foreign material. I have found that in most cases a fluidized bed depth of twelve to eighteen inches is satisfactory.

The air requirement both as to volume and pressure, for operating the trap is low. A small blower is normally satisfactory for the purpose, or in certain cases where the air-gravity conveyor is used, air may be supplied to the plenum chamber from the air chamber of the conveyor.

In an actual embodiment of the invention in which the porous medium in the trap was a low permeability woven fabric of the type referred to below, a trap and conveyor of the type illustrated in Figs. 8 and 9 was employed in handling a cement raw material mixture having a fineness of about 90% minus 200 mesh. Pulverulent materials require vertical gas velocities of 0.05 to 0.3 feet per second i. e. 3 to 18 C. F. M./sq. ft. of bed

area to maintain maximum fluidization. In this case, about 4 C. F. M./sq. ft. were used and were passed through the bed with a pressure of 28" w. g. (1 lb. p. s. i.) in the plenum chambers of the trap. The fluidized bed varied in depth from about 7" at the ends to 16" in the center. The raw material passed through the 6" wide conveyor at a rate of 25 T./hr. in a bed about 1½" deep. A variety of foreign materials including nuts and bolts, screen wire pieces, shattered grinding balls, metal cuttings, and rock oversize of different dimensions, were added to the flowing stream about 10 feet ahead of the trap. The trap was emptied while the stream continued to flow. Substantially 100% of the metal objects were thus recovered, 90% of the ¼ inch oversize and about 50% of the ½ inch oversize.

In the embodiment of my invention illustrated in Figs. 6-9, a woven fabric of low permeability is preferred in order to promote uniform air distribution through the entire bed in spite of the substantial difference in material head between the center and ends of the trap. I have found that a fabric having a permeability below about 5 is best suited for this purpose. This is equivalent to the porous medium described in Schemm U. S. Patent No. 2,527,455 for use in the air activated gravity conveyor, which is the conveyor used in the above described test. In this installation, more highly permeable members would cause excessively aerated portions of the bed near the ends, with a relatively dead area in the center, thus decreasing the efficiency of separation of foreign materials. In the other modifications of my trap it is frequently preferred to use porous mediums of similar low permeability to promote uniform distribution of air.

I claim:

1. An apparatus for separating foreign material from a stream of material moving through a conveyor trough, a container disposed beneath the trough and in communication with the interior thereof, a pair of aeration units within the container, each unit including a plenum chamber closed at its top by a flat gas-permeable wall and the units being disposed at opposite sides of the container with their top walls lying at opposite angles to the vertical and defining a wedge-shaped bottom for the container, one unit being longer than the second and having its lower end beneath and spaced from the lower end of the second unit, a discharge port between the lower ends of the units, a gate operable to open and close the port, and means for supplying a gas under pressure to the plenum chambers for diffusion through the gas-permeable walls into the contents of the container.
